UNITED STATES PATENT OFFICE.

JAMES T. PHILLIPS, OF GRAND RAPIDS, MICHIGAN, ASSIGNOR TO THE ALDINE MANUFACTURING COMPANY, OF SAME PLACE.

DESIGN FOR A FIRE-BOARD.

SPECIFICATION forming part of Design No. 22,635, dated July 18, 1893.

Application filed March 10, 1893. Serial No. 465,431. Term of patent 7 years.

To all whom it may concern:

Be it known that I, JAMES T. PHILLIPS, of Grand Rapids, Kent county, State of Michigan, have invented and produced a new and 5 original Design for Fire-Boards for Mantels, of which the following is a specification.

In the drawings Figure 1, is a front view and Fig. 2, a profile view of a fire board having my design.

10 The leading feature of the design is in the ornamental surface configuration. The fire board is shown as designed to cover the fire place opening. Centrally thereof is a wreath of conventional shape terminating in a bow 15 and streamers. Around this are ornamental

parallel beads or raised lines and in the panel extending across the top are a series of loops terminating in streamers extending down each side panel while at the base of each side panel is an ornamental spray. 20

What I claim is—

The design for a fire board herein shown and described.

In testimony whereof I affix my signature in presence of two witnesses.

JAMES T. PHILLIPS.

Witnesses:

CHAS. M. WILSON,
JOHN E. MORE.
